TONGUE-DEPRESSOR DISPENSER

Norbert Leopoldi, 4180 Marine Drive,
Chicago, Ill. 60613

Filed May 29, 1968, Ser. No. 12,121

Term of patent 14 years

Int. Cl. D20—02; D9—06

U.S. Cl. D52—2

In FIGURES 1, 2 and 4 the individual tongue-depressors are shown in phantom lines for illustrative purposes only.

The dominant features of the design reside in the full line portions.

I claim:

The ornamental design for a tongue-depressor dispenser, substantially as shown and described.
